CARD HOLDER

Garcelia Valles Soriano, 1545 Mantua Ave.,
Coral Gables, Fla. 33146

Filed Sept. 15, 1969, Ser. No. 19,139

Term of patent 14 years

Int. Cl. D20—03

U.S. Cl. D96—3

FIG. 1 is a front elevational view of a card holder showing my new design;

FIG. 2 is a rear elevational view thereof; and

FIG. 3 is a left side elevational view thereof, the right side being a mirror image of the side shown.

I claim:

The ornamental design for a card holder, as shown and described.
